J. M. LEA

PUMP

Filed May 2, 1927

Inventor

John M. Lea

UNITED STATES PATENT OFFICE.

JOHN M. LEA, OF DETROIT, MICHIGAN.

PUMP.

Application filed May 2, 1927. Serial No. 188,112.

- The invention relates to improvements in pumps, as described in the present specification and illustrated in the accompanying drawings that form part of the same.
- 5 The invention consists essentially in the novel arrangement and construction of parts whereby a plurality of pump units are connected between common headers and electrically insulated for individual independent 10 operation in parallel.
- The objects of the invention are to provide a pump comprising units which may be readily coupled together to give a desired delivery capacity and at the same time provide 15 a coupling means which will provide proper insulated connections for conducting an operating electric current and also serve as a multiple mounting bracket.
- In the drawings,
- 20 Figure 1 is a plan view of a three-unit pump and header connections.
- Figure 2 is a cross-sectional view on the line 2—2 in Figure 1.
- Figure 3 is a plan view of one unit of a 25 pump showing a modified connection to the headers and supporting bracket.
- Like numerals of reference indicate corresponding parts in each figure.
- Referring to the drawings, and particularly 30 Figures 1 and 2, the numeral 10 designates a pump unit the details of which are not concerned in the present invention, other than the fact that each pump unit has an inlet 11 and outlet 12 controlled by suitable 35 valves and a magnetically operated pumping mechanism (not shown) contained in the lower portion 13 forming the body of the pump.
- In the present pump three units 10 are 40 shown connected between a pair of headers 14 and 15 which serve, as hereinafter explained, to operatively connect the several units in multiple, and provide an electrically insulated mounting for the same.
- 45 The headers 14 and 15 are alike and each preferably made from extruded square tubing with a round center bore 16 extending throughout its length, and which may be readily threaded for a short distance at each 50 end to receive standard pipe fittings. The headers 14 and 15 also have the cross bores 17 extending laterally through the center passage 16 and arranged one opposite the inlet and outlet of each unit 10.
- 55 The units 10 are secured between the pair of square-shaped headers 14 and 15 by cap-screws 18 inserted through the cross-bores 17 in the headers from the outer side, and threaded into the correspondingly threaded inlets 11 and outlets 12 of the units 10, suitable washers 19 of insulating material being provided on each side of the headers to electrically insulate the same from the cap-screws and the pump units and to serve as a packing to prevent leakage of liquid while the pump is operating.
- 60 Each header cap-screw 18 has a central passage 20 extending from its inner end to a point near its head, and also has the side orifices 200 communicating with the central passage 20 and the passage 16 in the headers, so that each header cap-screw not only connects the units 10 between the headers, but also completes a liquid passage therebetween.
- 65 It should also be noted that the header cap-screws are reduced where they extend through the headers to leave an ample passage in the headers and to stand insulated therefrom. It is also preferable to have the outside insulating washers 19 on the cap-screws 18 extend a little into the cross-bores 17 in the headers to properly line up the entire assembly and definitely insulate the 70 pump unit as described, as it will be understood that the magnetic circuit of each unit is grounded to the pump body as one terminal connection.
- 75 The three units 10 as shown in Figure 1 of the drawings thus form a multiple pump, and a suitable intake connection 21 may be made at one end of the header 14, and a similar outlet connection 22 may be made at one end of the header 15, the other ends of 80 said headers being closed by plugs 23.
- 85 Each unit 10 has a separate pumping mechanism as hereinbefore referred to, and one electrical lead 24 is connected to an insulated terminal screw 25 on each unit, from which proper electrical connection is made to the operating solenoid or other mechanism, and thence to the body of the pump unit, and a second electrical lead 26 to the terminal screws 27 threaded into the outer 90 ends of the cap-screws 18 of a header.
- 95 The assembly as above described completes a three-unit pump with each unit capable of independent action and a much more regular flow of liquid through the headers.
- 100 It will also be readily seen that the failure of one unit will in no manner affect the 105 110

others, and it may be removed and replaced without disturbing the others or their connections.

The arrangement of units and headers as described also lends itself admirably to a bracket mounting such as the L-shaped brackets 28 and the plates 29 clamped over the header 14 and the heads or upper portions of the pump units 10 by the screws 10-30 and having the pads 31 of insulating material between them and the header.

Referring particularly to Figure 3, a mounting is shown in which only a single electrical lead wire 32 is used, and the return 15 current grounded through the pump and its mounting.

The unit 10 is assembled between the headers 14 and 15 just as described with reference to Figures 1 and 2, except that it 20 is not necessary to insulate the header cap-screws and only packing or gasket washers are used. Also in this figure a cap-screw 33 is shown with a central passage 34 extending throughout its length and the outer 25 end enlarged to receive an outlet connection 35.

The bracket in this figure is shown as a single piece 36 connected to the ends of the headers 14 and 15 by the plug screw 37 and 30 the bushing 38, to which an intake connec-

tion 39 may be made, and of course any number of units may be headed up as desired to complete any required capacity of pump.

Such changes are exemplary of the modifications which may be made in the specific 35 details and arrangement of parts without departing from the spirit of the invention as set forth in the annexed claims.

I claim:

1. A pump comprising a plurality of 40 pumping units each having an inlet and an outlet, a pair of headers each having a central passage with cross-bores opposite each of said units and hollow cap screws extending through said cross-bores into the inlet and outlet openings of said units and completing passageways between said headers.

2. A pump comprising a pair of fabricated metal headers having opposed flat outside faces and a round center bore threaded at 50 the ends to receive standard pipe fittings and cross bores extending therethrough, a plurality of pump units each having an inlet and an outlet opening and coupling screws extending through said headers and securing the cross bores thereof in communication 55 with the inlet and outlet openings of said units.

In testimony whereof I affix my signature.

JOHN M. LEA.
